US00D994777S

(12) **United States Design Patent** (10) **Patent No.:** **US D994,777 S**
(45) **Date of Patent:** **** Aug. 8, 2023**

(54) **GAME CONTROLLER**

(71) Applicant: **Valve Corporation**, Bellevue, WA (US)

(72) Inventors: **Carl Samuel Conlee, IV**, Seattle, WA (US); **Philip Bryan**, Bellevue, WA (US); **Claire Gottschalk**, Bellevue, WA (US); **Jeremy Slocum**, Sammamish, WA (US)

(73) Assignee: **Valve Corporation**, Bellevue, WA (US)

(**) Term: **15 Years**

(21) Appl. No.: **29/843,751**

(22) Filed: **Jun. 23, 2022**

Related U.S. Application Data

(62) Division of application No. 29/764,718, filed on Dec. 31, 2020, now Pat. No. Des. 960,244, which is a division of application No. 29/648,235, filed on May 18, 2018, now Pat. No. Des. 908,798.

(57) **CLAIM**

The ornamental design for a game controller, as shown and described.

DESCRIPTION

FIG. 1 is a back perspective view of a game controller; FIG. 2 is a front perspective view thereof; FIG. 3 is a front view thereof; FIG. 4 is a back view thereof; FIG. 5 is a left-side view thereof; FIG. 6 is a right-side view thereof; FIG. 7 is a top view thereof; and, FIG. 8 is a bottom view thereof. FIGS. 1-8 illustrate a right-hand game controller; it is understood that the views of a left-hand game controller are mirror images of the views shown in the FIGS. 1-8.

The broken lines depict portions of the game controller that form no part of the claimed design.

1 Claim, 8 Drawing Sheets
